UNITED STATES PATENT OFFICE.

CHARLES STARYSKY, OF WICHITA FALLS, TEXAS.

PUMP.

Application filed July 6, 1925. Serial No. 41,735.

This invention relates to apparatus for pumping wells, particularly oil wells, and it consists of the constructions, combinations and arrangements herein described and 5 claimed.

An object of the invention is to provide an oil well pump by the use of which the pumping off of any size of well is facilitated to a great extent in this that the pump operates without requiring the use of extra tubing, pump rods, additional casing, etc.

Another object of the invention is to provide a pump in which an embodied packer is arranged to be actuated at the desired 15 depth as to fix the pump in the working position in the well casing, the packer constituting a partition past which the oil is pumped to the surface.

A further object of the invention is to 20 provide a pump which is operated by a flexible cable, it being by means of the cable that the pump is lowered into the well casing whereupon the packer is set, secondly performing the pumping operation, thirdly again loosening the packer and finally withdrawing the pump from the well.

Another object of the invention is to provide a pump which can be lowered into and removed from a well in a very few minutes, 30 this being due to the fact that it is suspended wholly by a flexible cable that can be wound upon a reel or drum thereby eliminating the usual string of tubing or rod which requires considerable screwing up or unscrewing in 35 order to place them into or remove them from the well.

A further object of the invention is to provide a pump which is self containing, that is to say, all of the necessary mechanism is suspended from the cable, and when withdrawn from the well no parts whatever are left to offer obstructions to subsequent 40 operation.

Other objects and advantages appear in 45 the following specification, reference being had to the accompanying drawing, in which

Figure 1 is a sectional view of the lower end of a well casing showing the improved pump in position.

50 Figure 2 is a detail sectional view of the pump.

Figure 3 is a detail horizontal section on the line 3—3 of Figure 2.

The invention may aptly be termed a 55 "rodless" and "tubingless" pump for oil

or other wells, in that neither rods nor tubes are required to be used in order that the pump may function. It is quite customary in the art to operate pumps of all kinds, especially oil well pumps by a string of 60 rods. These rods are screwed together, and if the well is deep it is obvious that the work of screwing up and unscrewing the sections of rods will consume a great deal of time. It is also customary to use tubing in connection with such pumps. The tubing also comes in sections and the work of screwing up and unscrewing sections again consumes much time. By the use of the invention the work of screwing up and unscrewing both 65 rods and tubing is eliminated in that neither rods and tubing are used.

Referring to the drawing, the customary well casing is indicated at 1. The cable 2, which now replaces the customary pump 75 rod, makes connection at the cable socket 3 with what is herein known as the weight joint 4. This weight joint combines the functions of connecting the cable with the pump plunger 5 and expanding the packer 60 6 within the well casing 1.

For the first purpose the weight joint 4 has suitable connection with the stem 7 of the plunger 5. For the second purpose it carries a substantial disk-plate (Fig. 2) 85 which is capable of being let down upon the lower abutment 9 so that the weight of the weight joint is imposed upon the skeleton joint 10 and so transfers it to the packer 6. The skeleton joint is internally threaded at 90 11 to receive the threaded end 12 of the packer. The opposite threaded end 13 of the packer is screwed into the upper internally threaded end of the perforated liner 14. The packer may be of any ordinary construction similar, for example, to that disclosed in U. S. Patent No. 451,769, which construction usually involves the use of a 95 rubber or other flexible body capable of expansion (under pressure).

A third function of the weight joint 4 is to assist in the extraction of the pumping apparatus from the well casing. To this end the disk 8 is brought into engagement with the upper abutment 15 whereupon an upward pull will first contract the packer 6. After having once set the apparatus in the appropriate position in the well casing, limited reciprocation of the weight joint by means of the cable 2 actuates the plunger 105 110

5. During this reciprocation the disk 8 touches neither of the abutments 9 and 15, but if it should no harm will result.

Oil is drawn into the pump barrel 16 through the foot valve 17 upon the aforesaid operation of the plunger 5. The oil is first drawn through the strainer 18 which is attached to the lower extremity of the pump barrel. The perforated liner is closed by a plug 19 at the bottom, which, in the event that the perforated liner is used alone (Fig. 2) will rest on the bottom of the well 4. The working conditions of various wells may require the addition of one or more liners 20 (Fig. 1) in which case such additional liner is connected by means of a coupling 21, and the lower end of the added liner is closed by a plug 19^a, corresponding with the plug 19.

20 A cap 22 closes the upper end of the skeleton joint 10. The weight joint 4 passes through an opening in the center of the cap. The weight joint is not intended to bear against the lower and upper abutments 9 and 15, the openings through which the weight joint passes being a trifle larger. These abutments are made conical in shape, as shown, and in practice are first cast and then fixed in the skeleton joint in any appropriate manner.

Provision is made for the application and removal of the disk 8 by making this disk in sections (Figs. 2 and 3) and connecting the sections by bolts 26 at the lapped joints 24. The sections fit in a peripheral groove 25 in the weight joint 4. Access to the bolts of the disk is had through an opening 26 (Fig. 1) in the wall of the skeleton joint. This skeleton joint, as has been stated, is 40 slotted at 27 for the outlet of the oil. These slots extend into close proximity with the upper end of the packer 6, the arrangement being of especial value in aiding in the disposition of sand after a cessation of 45 operation of the pump.

The operation is now readily understood. The well bore is made in the usual manner, and the casing 1 is let down as the depth increases, all according to practice. 50 The well casing is generally stopped in the region of a strata of rock or shale. The pumping apparatus is let down by the cable 2. Working conditions vary in different wells, and the pumping apparatus is adjusted to agree with the behavior of various wells.

One well may be of such nature that the perforated liner 14 can be let down all the way to the bottom (Fig. 2). Another well 60 may make it desirable to elevate the liner from the bottom, in which case an unperforated liner 20 is added (Fig. 1) and that liner rests on the bottom. According to this principle one or more unperforated 65 liners can be supplied as needed, but this is

not uncommon in practice. In any event the engagement of the pumping apparatus with the bottom of the bore produces a stop for the lower part of such apparatus. Subsequent relaxation of the cable 2 permits 70 the disk 8 (Fig. 2) to come into engagement with the lower abutment 9 so that the weight of the weight joint 4 is imposed upon the skeleton joint 10 and so transferred to the packer 6. The packer thereupon expands within the casing 1 and produces a partition in the well casing. The setting of the packer is done without either the aid or weight of well tubing as is usually the case. Reciprocation of the weight joint 80 4, by appropriate operation of the cable 2, in turn reciprocates the pump plunger 5 within the barrel 16 so that oil is drawn through the strainer 18 and fits the valve 17 into the barrel and discharge at the slots 85 27 into the well casing above the packer. The usual string of sucker rods is eliminated. It is observed that the pump barrel 16 is attached to and suspended from packer 6 but extends no farther than the top 90 of the threaded end 12. It has been explained that the slots 27 extend down into proximity with the upper end of the packer. The advantage of this arrangement is this:

The difficulties attending the sanding of 95 a well are commonly known and recognized. A well is most likely to sand up after a period of idleness. The sand is carried by the oil which is in a more or less turbulent condition while being pumped, and when 100 pumping ceases the sand will settle upon the top of the packer 6. Upon starting the pumping apparatus again it will require but a few strokes of the pump plunger 5 to force oil through the barrel 16 and through 105 the slots 27. This action at once dislodges the sand from the top of the packer and the operation of the pumping apparatus proceeds normally.

It is the work of but very few minutes to 110 wind the cable 2 upon an appropriate reel at the surface and thus lift the entire apparatus out of the well. In such case the disk 8 will engage the upper abutment 15, lifting up upon the skeleton joint 10 and 115 cause contraction of the packer so that the apparatus is loosened from the well casing 1. The extremely arduous labor of unscrewing numerous tubing sections and sucker rods is entirely eliminated. It is 120 possible to use any size of pump barrel 16 to agree with the capacity of the well. If the well is found to have a large flow, the pump barrel can be increased in size to correspond.

Relative adjustments of the pump barrel 125 can also be made. If found desirable, the pump barrel may be located down inside of the liner 20 (Fig. 1) instead of inside of the perforated liner 14. This adjustment is accomplished by the obvious expedient of 130

simply interposing a section of piping between the packer 6 and the pump barrel. In no case is the actual pumping apparatus disturbed or subjected to strain in either 5 setting or releasing the packer. The packer is set by pumping the liner upon the bottom either directly or indirectly, and is released by pumping the disk 8 against the abutment 15. In the latter instance an upward pressure of many tons can be exerted to release 10 the packer.

I claim:—

1. Apparatus of the character described comprising a pumping unit, a flexible operating and supporting cable by which said unit is first lowered into a well casing, is then operated to pump fluid and is finally abstracted from the well casing, an expandable packer, and means operatively connecting 15 the pumping unit and cable having an abutment member thereon cooperating with said unit in one direction of movement to expand the packer in the first instance thereby to sustain the unit in operative position 20 within the well casing and cooperating with said unit in the reverse direction of movement subsequently to release the packer preparatory to the abstraction of the unit from 25 the well casing.
2. Apparatus of the character described comprising a reciprocating cable, a weight attached to the cable and having an abutment disc thereon, a pump plunger suspended from the weight, a pump barrel in which 30 the plunger operated to pump by reciprocating movement of predetermined and limited extent, an expandible packer, from which the pump barrel is suspended, means including a skeleton joint by which the packer is suspended and through which the weight passes, said skeleton joint having spaced upper and lower abutments thereon in the plane of movement of the weight disc and engaged thereby upon reciprocatory motion 35 of the plunger beyond said predetermined extent in a downward direction to expand the packer and in an upward direction to contract and release the packer preparatory to the removal of the pump barrel 40 from the well.
3. The combination in apparatus of the character described of an expandible packer

to be fixed in position in a well casing to constitute a partition, a tubular support from which the packer is suspended having 55 slots therein adjacent to the packer, a pump plunger, and a pump barrel in which the plunger is operable, said barrel terminating substantially flush with the top of the packer so that any sand accumulating on top of 60 the packer may immediately be dislodged through the slotted support immediately above the beginning of the operation of the plunger.

4. The combination in apparatus of the character described comprising an expandible packer arranged to be fixed in a well casing, a plunger, a weight joint to which the plunger is attached for operation by reciprocation of the joint, a pump barrel in 70 which the plunger operated, said barrel being suspended from the packer and being substantially flush with the top of the packer, and a skeleton joint from which the packer is supported and in which the weight 75 joint is movable, said joint having openings adjacent to the top of the packer for the prompt dislodgment of sand on top of the packer by operation of the plunger in the barrel.

5. Apparatus of the character described comprising an operating and supporting cable, a weight joint connected to the cable, a plunger suspended from the weight joint, a pump barrel in which the plunger is operable by reciprocation of the cable, an expandible packer from which the barrel is suspended, a skeleton cable, an expandible packer from which the barrel is suspended, a skeleton joint from which the packer is supported provided with slots adjacent to the packer for the dislodgment of sand, lower and upper abutments in spaced relationship in the skeleton joint and a separable disk carried by the weight joint having limited 85 determinate reciprocation between the abutments in ordinary operation of the plunger but being engageable by excess reciprocation with the lower or upper abutments to either expand the packer within a well casing or to 90 contract said packer preparatory to withdrawal of the pumping apparatus respectively.

CHARLES STARYSKY.
